GUANYLUREA SALTS OF PENICILLIN

Lawrence Ritter, Valley Cottage, and Joseph F. Weidenheimer, Red Park, Pearl River, N. Y., assignors to American Cyanamid Company, New York, N. Y., a corporation of Maine

No Drawing. Application January 24, 1952,
Serial No. 268,132

8 Claims. (Cl. 260—239.1)

1

Our invention relates to a new series of penicillin derivatives, and their preparation, which are comparatively water insoluble organic penicillin salts of such characteristics that the penicillin is comparatively insoluble; and in many of which the penicillin is therapeutically available as such, and the salt is non-toxic. More particularly one aspect of the invention relates to salts of penicillin which are slightly soluble so that when injected for penicillin therapy the penicillin is made available to the subject over a prolonged period whereby a therapeutically effective penicillin blood level is maintained for a longer period than would be possible by the use of penicillin as an alkali metal salt. The range of solubility of our new salts is such that the blood level and duration of therapeutic effectiveness may be controlled to a large extent by selecting a particular one of our salts or a mixture thereof; the variation in solubilities being such that the time may be varied over a wide range in accordance with the user's requirements. This application is a continuation-in-part of Serial Number 108,238, filed August 2, 1949, entitled "Slightly Soluble Penicillin Derivatives and Methods of Making the Same," now abandoned in favor of the present application.

As an additional advantage, these salts may be formed to aid in the separation or purification of penicillin in its manufacture and isolation; and for such purposes the salt selected may be comparatively toxic, if the toxic radicals are removed or their toxicity neutralized before the therapeutic use of the penicillin. It has been found that the non-toxic compounds of this invention may readily be used for the injection of patients with such a quantity of a penicillin salt that a therapeutically useful concentration of penicillin may be maintained in the blood level of the normal patient for a period of over 96 hours; so that in many conditions for which penicillin therapy is indicated, particularly certain venereal diseases, a single injection is sufficient for an adequate course of treatment.

Also, our salts exhibit remarkable stability as compared with other forms of penicillin, such as the alkali metal salts. Accordingly, our salts make valuable additives for feedstuffs for poultry, animals or other organisms, whether used singly or in combination. The conventional forms of penicillin, such as the alkali metal salts of penicillin, are too sensitive to moisture to make satisfactory additives for feedstuffs.

The composition of this invention has as an essential element thereof the reaction product of

penicillin or one of its salts with a guanylurea, or a salt of a guanylurea, such as an acid salt thereof, thereby forming a guanylurea salt of penicillin. These salts are slightly soluble, and those selected for therapeutic use are non-toxic. The solubility of the penicillin G salt of guanylurea itself is 1.31% in water at room temperature. The salts in which there is a substituent present on the guanylurea nucleus are in general less soluble. For example, benzoylguanylurea penicillin G has a solubility of 0.0846% in water at room temperature. The salts of the other penicillins are comparable.

More particularly, our invention includes the particularly useful salts of penicillin, such as penicillin G, F, X, or other penicillin, with a basic compound from the group consisting of guanylurea and compounds containing a guanylurea nucleus on which there is present at least one of the following radicals: alkyl, including N-N link alkylene with from 3 to 5 carbon atoms, alkenyl, alkynyl, cycloalkyl, monocyclic aryl, polycyclic aryl, carbamyl, monocyclic aroyl, 5-membered monocyclic heterocyclic radicals and 6-membered monocyclic heterocyclic radicals with nitrogen, sulfur and oxygen hetero atoms, including such radicals on the aliphatic portions of which are present groups such as hydroxy, alkoxy, aryl and nitrile groups, and on the aromatic portions of which are present groups such as alkyl, aryl, halogen, nitro, alkoxy, aryloxy, nitrile, hydroxy and carbethoxy groups.

These materials are soluble to such an extent that when injected into the subject the penicillin is stored as a deposit but released to the blood stream in a therapeutically effective form at such a rate as to maintain a certain blood level but not at a sufficient rate so that the penicillin activity is dissipated over an undesirably short period. The level and the duration may be controlled by the selection of a particular guanylurea. Among the guanylureas many compounds containing the guanylurea nucleus besides guanylurea itself are effective. Among such are the alkyl guanylureas such as methyl, butyl, octyl or dodecyl guanylurea penicillin; the cycloalkyl guanylureas such as cyclohexylguanylurea penicillin; the acyl guanylureas, both aromatic and aliphatic, such as benzoylguanylurea penicillin (note Patent 2,397,667); the aromatic guanylureas such as para-chlorophenylguanylurea penicillin and di-para-chlorophenylguanylurea penicillin, and phenylguanylurea penicillin; carbamylguanylurea penicillin, which may be regarded as the acyl derivative of carbamic acid; and multi-

substituted guanylureas in which the substituents may even be joined, as for example, N₁-pentamethylene guanylurea penicillin. The solubilities vary but are within the useful ranges. The field of suitable guanylureas is limited more by availability than by other technical considerations; the guanylureas which may be conveniently prepared all appear to be suitable for forming comparatively insoluble salts and the non-toxic guanylureas appear to be satisfactory for direct injection into patients.

Many guanylureas are known which will form salts with penicillin. As illustrative, but in no way limiting, examples of certain such guanylureas are:

Aliphatic guanylureas

Methylguanylurea
Dimethylguanylurea
Ethylguanylurea
Diethylguanylurea
Propylguanylurea
Dipropylguanylurea
Isopropylguanylurea
Disopropylguanylurea
Butylguanylurea
Dibutylguanylurea
Hexylguanylurea
Dihexylguanylurea
2-ethylhexylguanylurea
Di-2-ethylhexylguanylurea
Heptylguanylurea
Dihexylguanylurea
Octylguanylurea
Diocetylguanylurea
Nonylguanylurea
Dinonylguanylurea
Decylguanylurea
Didecylguanylurea
Undecylguanylurea
Diundecylguanylurea
Dodecylguanylurea
Ditridecylguanylurea
Tridecylguanylurea
Ditridecylguanylurea
Tetradecylguanylurea
Ditetradecylguanylurea
Pentadecylguanylurea
Dipentadecylguanylurea
Hexadecylguanylurea
Dihexadecylguanylurea
Heptadecylguanylurea

Diheptadecylguanylurea
Octadecylguanylurea
Diocadecylguanylurea
Nonadecylguanylurea
Dinonadecylguanylurea
Allylguanylurea
Diallylguanylurea
Crotylguanylurea
Dicrotylguanylurea
3-propynylguanylurea
Ethylenediguanlurea
Propylenediguanlurea
Cyclohexylguanylurea
Cyclopentylguanylurea
Dicyclopentylguanylurea
Benzylguanylurea
Alpha-phenylethylguanylurea
Beta-phenylethylguanylurea
Alpha-phenylisopropylguanylurea
Beta-phenylisopropylguanylurea
Alpha-phenyl-n-propylguanylurea
Beta-phenyl-n-propylguanylurea
Gamma-phenyl-n-propylguanylurea
Naphthylmethylguanylurea
Phenylallylguanylurea
Phenylpropargylguanylurea
Hydroxyethylguanylurea

Aromatic guanylureas

Phenylguanylurea
Chlorophenylguanylurea
Tolylguanylurea
Xylylguanylurea
Ethylphenylguanylurea
Isopropylphenylguanylurea
Butylphenylguanylurea
Isobutylphenylguanylurea
Methoxyphenylguanylurea
Ethoxyphenylguanylurea
Bromophenylguanylurea

Iodophenylguanylurea
Nitrophenylguanylurea
Carbethoxyphenylguanylurea
Aminophenylguanylurea
Meta-hydroxyphenylguanylurea
Para-hydroxyphenylguanylurea
Acetaminophenylguanylurea
Cyanophenylguanylurea

Acylguanylureas

Acetylguanylurea
Propionylguanylurea
Butyrylguanylurea
Valerylguanylurea
Caprovinylguanylurea
Enanthylguanylurea
Caprylylguanylurea

Palargonylguanylurea
Caprylguanylurea
Laurylguanylurea
Myristylguanylurea
Palmitylguanylurea
Stearylguanylurea
Carbamylguanylurea

Heterocyclic guanylureas

Triazolylguanylurea
Thiazolylguanylurea
Imidazolylguanylurea
Thiazolidineguanylurea
Imidazolidineguanylurea
Pyrazolylguanylurea
Pyrazolidineguanylurea
Furylguanylurea
Thienylguanylurea
Pyrrolidylguanylurea
Morpholinylguanylurea
Thienoquinolylguanylurea
Furoylguanylurea

Pyridylguanylurea
Pyrrolylguanylurea
Furfurylguanylurea
Pyranylguanylurea
Thienylguanylurea
Indolylguanylurea
Quinolylguanylurea
Isoquinolylguanylurea
Carbazolylguanylurea
Acridinylguanylurea
Xanthinylguanylurea
Pyrimidylguanylurea
Quinoxalylguanylurea
Piperidylguanylurea

Mixed alkyl-aryl guanylureas

N phenyl N methylguanylurea
N phenyl N ethylguanylurea
N phenyl N propylguanylurea
N phenyl N butylguanylurea
N phenyl N hexylguanylurea
N phenyl N cyclohexylguanylurea
N chlorophenyl N methylguanylurea
N chlorophenyl N butylguanylurea
N chlorophenyl N cyclohexylguanylurea
N xylyl N ethylguanylurea
N tolyl N isopropylguanylurea
N hydroxyphenyl N ethylguanylurea

Particularly useful salts are formed if the aliphatic radicals above listed have such substituents as hydroxy radicals, alkoxy radicals, aryl radicals, or nitrile radicals; also, the aromatic radicals may have such substituents as alkyl, aryl, halo, nitro, alkoxy, aryloxy, nitrile, hydroxy and carbethoxy radicals. To list each of such useful guanylureas would unduly lengthen the list.

Better yields are obtained if the substituents are such that they do not react with each other or functional groups on the penicillin moiety. However, useful yields may be obtained with such reactive groups.

Preparation

The penicillin derivatives may be prepared by the use of a free guanylurea base and free penicillin but inasmuch as penicillin is normally more conveniently commercially available as a salt such as for example the sodium salt of penicillin G, potassium salt of penicillin G or of penicillin F, silver salts of the various penicillins, the amine salts such as triethylamine salt, etc., and as the guanylureas are generally more conveniently available as an acid salt such as the hydrochloride, the sulfate, the nitrate, the phosphate, the acetate, etc., it is normally more convenient to use the acid salts of a guanylurea and a basic salt of a penicillin than otherwise. The reaction may be conveniently carried out in water, methanol, ethanol, propanol, butanol, 2-ethoxyethanol, 2-methoxyethanol, other alkoxy ethanols, other alcohols, dioxane, acetone, methylethyl ketone, methylisobutyl ketone, mixtures of two or more of these solvents or other common solvents. Because water is the cheapest, it is most conveniently used.

For most purposes penicillin G is selected as the form of penicillin of choice because penicillin G has met with greater acceptance by the medical profession than the other penicillins, but it is to be understood that if for a particular treatment some other penicillin or a mixture of penicillins is desired, these may be used. For use therapeutically, it is normally desired that the inert materials injected be held to a minimum and accordingly guanylureas of a lower molecular weight are more desirable so as to not overburden the body with an unduly large weight ratio of inert material. For therapeutic use the penicillin salt of a particular guanylurea is most frequently formed with an inert salt as for example sodium chloride, resulting from the salts used in its formation. These inert salts may be removed but are frequently found to be desirable as they increase the salinity of the material. Normally the crystal habit in which the crystals are formed is suitable for injection but in some instances recrystallization in suitable solvents may be desired.

For purposes of injection the material may be suspended in a suitable medium such as distilled water, normal saline, 20% propylene glycol or other commonly used aqueous diluents or an oil such as peanut oil, sesame oil, cottonseed oil or other assimilable tri-glyceride together, in every case, with such stabilizing agents, buffers, thixa-

tropic agents, viscosity modifiers and wetting agents as may be desired to cause the material to have fluidity and stability such that it may be easily filled into a hypodermic syringe and ejected therefrom into the subject.

In addition to a guanylurea penicillin salt or a mixture thereof, it is frequently desirable to have a sodium, potassium or calcium salt of penicillin additionally present so as to insure a high initial blood level of penicillin in the subject as well as a prolonged blood level resulting from a guanylurea penicillin.

Guanylurea itself has the formula

For purposes of nomenclature, the compounds of this invention can be considered as penicillin salts of the guanyl derivatives of urea. By analogy to the nomenclature of the amidine derivatives, the nitrogen of the $=\text{NH}_2$ group is designated N, and the nitrogen of the $=\text{NH}$ group as N'. All the derivatives in the specific examples and claims have the substituents on the nitrogen of the NH_2 group. Some confusion in terminology exists with respect to the term "aryl." For purposes of the present claims, "aryl" is used to refer to hydrocarbon radicals.

As illustrations of certain of the suitable guanylurea salts, but not by way of limitation, there are herewith set forth certain specific examples.

The various guanylureas themselves may be prepared in various fashions. A convenient method of preparation is by starting with the acid addition salt of an amine and a metallic salt of dicyanamide and reacting the materials in substantially molar proportions to form substituted cyanoguanidine. Certain improvements in the method of formation are set forth in a patent of Bryan C. Redmon and Daniel E. Nagy, 2,455,807, December 7, 1948, entitled "Preparation of Substituted Cyanoguanidine." The thus formed substituted cyanoguanidine may then be reacted with water in the presence of a strong mineral acid to form a corresponding guanylurea.

Certain of the acyl guanylureas which are suitable for the purpose of our invention, are described in detail in a patent to Donald W. Kaiser and Jack T. Thurston, 2,397,667, April 2, 1946, entitled "Acyl-Guanylureas and Their Preparation."

As a specific example to illustrate the general method, n-octylguanylurea neutral sulfate dihydrate,

may be prepared from n-octylidicyandiamide prepared from octylamine sulfate and sodium dicyanamide. To 100 grams of the octylidicyandiamide is added 200 milliliters of concentrated hydrochloric acid and 75 milliliters of dioxane. The mixture is heated on a steam bath for an hour, then distilled under reduced pressure to remove the dioxane. To the residue is added 200 milliliters of water, and then 150 grams of sodium sulfate. The n-octylguanylurea neutral sulfate separates as an oil which later solidifies, the mixture is filtered, the solid slurried in water, again filtered, and is dried in a desiccator. The gummy product is extracted with acetone, leaving 65 grams of the acetone insoluble material which is recrystallized from a mixture of 1400 milliliters

of water and 400 milliliters of ethanol thereby yielding the dihydrate of octylguanylurea neutral sulfate, melting point 110° C. (softens).

EXAMPLE 1

Guanylurea penicillin

25.9 grams of crystalline sodium penicillin G is dissolved in 50 milliliters of distilled water and added slowly to a solution of 10 grams of guanylurea hydrochloride in 20 milliliters of distilled water at room temperature. After approximately $\frac{1}{3}$ of the penicillin solution is added, crystals of guanylurea penicillin begin to appear. The remaining penicillin solution is then added dropwise and the suspension cooled to and stirred at 4° C. for 4 hours to permit substantially complete precipitation of the desired product. There is thereby obtained 30.2 grams of guanylurea penicillin, with a melting point of 151-152° C. which has a theoretical analysis of 1360 units of penicillin activity per milligram and which on laboratory analysis is found to possess 1357 units per milligram. Theoretically the material possesses an analysis of:

	Percent
Carbon	49.54
Hydrogen	5.53
Nitrogen	19.26

For one specific run an analysis showed the product to contain:

	Percent
Carbon	48.89
Hydrogen	5.58
Nitrogen	19.05

The product is soluble in water to the extent of 1.31% at 25° C.

EXAMPLE 2

Cyclohexylguanylurea penicillin

5 parts of cyclohexylguanylurea hydrochloride is dissolved in 100 milliliters of distilled water and thereto is added a solution of 7.5 parts of crystalline sodium penicillin G dissolved in 100 parts of distilled water. A heavy crystalline precipitate of cyclohexylguanylurea penicillin is thereby formed. The material is allowed to cool for about 4 hours at 4° C. and the precipitate collected on a sintered glass filter, washed with water, and dried in vacuo over phosphorus pentoxide. The material has a theoretical content of 1100 units per milligram and on analysis was found to contain 1044 units per milligram. The material is soluble to the extent of 0.354% in water.

EXAMPLE 3

n-octylguanylurea penicillin

7 parts of n-octylguanylurea sulfate dihydrate is dissolved in water by warming on the steam bath. To the clear solution thus obtainable is carefully added a solution containing 7 parts of

crystalline sodium penicillin G in 50 parts of water; a heavy crystalline precipitate of *n*-octylguanylurea being formed. This is collected on a sintered glass funnel, washed, and dried in vacuo. There is obtained a product soluble to the extent of about 0.112% in water with an actual analysis of 1023 units per milligram as contrasted with the theoretical analysis of 1080 units per milligram.

EXAMPLE 4

*Dodecylguanylurea penicillin*3.9 grams of dodecylguanylurea hydrochloride is dissolved in a minimum of water and there is added thereto 45 milliliters of an aqueous solution containing a theoretical proportion of crystalline sodium penicillin G. A heavy white crystalline precipitate is formed which may be thinned with an additional 75 milliliters of water if desired to render filtration more convenient. The crystals are collected on a sintered glass funnel, washed with water, and dried. The product is soluble to the extent of 0.024% in water.

EXAMPLE 5

*Benzoylguanylurea penicillin*5 parts of benzoylguanylurea hydrochloride is dissolved in 100 parts of distilled water and thereto added a solution of 6.5 parts of crystalline sodium penicillin G in 50 parts of distilled water. A heavy crystalline precipitate of benzoylguanylurea penicillin G is thereby formed; which may be collected on a glass filter, washed with distilled water, and dried in vacuo. The product is soluble to the extent of 0.0846% in water and has an actual analysis of 916 units per milligram compared to a theoretical 1096 units per milligram. Whereas this material is insoluble its rate of hydrolysis is relatively high so that it is more available than would appear from the solubility characteristics alone.

EXAMPLE 6

*p-Chlorophenylguanylurea penicillin**p*-Chlorophenylguanylurea hydrochloride was obtained by the controlled acid hydrolysis of 1-*p*-chlorophenyl-3-cyanoguanidine. To 2.5 grams of this product suspended in 75 milliliters of distilled water there was added 3.5 grams of penicillin G dissolved in 25 milliliters of distilled water. The suspension was stirred for two hours, the precipitate collected, washed with water, and dried in vacuo. The material was found to have an actual analysis of 1019 units per milligram; the theoretical being 1088.

EXAMPLE 7

*Carbamylguanylurea penicillin*10

To a theoretical proportion of carbamylguanylurea hydrochloride dissolved in 100 parts of distilled water is added a solution of 6.5 parts of crystalline sodium penicillin G and 50 parts distilled water. A crystalline precipitate will be thereby formed which upon being collected on a suitable filter, washed, and dried, will be found to be carbamylguanylurea penicillin.

EXAMPLE 8

Guanylurea penicillin

To 50 parts of a free penicillin dissolved in 100 parts of ethanol is added a solution of a theoretical quantity of guanylurea, the free base, in 200 parts of distilled water. The two components may be mixed together, then cooled, and the crystals of guanylurea penicillin separated therefrom. The thus formed guanylurea penicillin will be found to be identical with that from Example 1.

EXAMPLE 9

Purification of penicillin

To a solution containing an impure penicillin estimated at a penicillin content of about 1 part per hundred, may be added an aqueous solution of dodecylguanylurea hydrochloride in water. A heavy white crystalline precipitate is thereby formed which upon being removed by filtration and washing, is found to be substantially identical with that from Example 4. This method of purification is particularly useful in the final steps of isolation of the penicillin and will frequently be found to render unnecessary the freezing and drying of the penicillin as a step in the purification.

EXAMPLE 10

*Beta-phenylethylguanylurea penicillin*40 45 50 55 60 65 70 75 80 85 90 95 98 100 103 106 109 112 115 118 121 124 127 130 133 136 139 142 145 148 151 154 157 160 163 166 169 172 175 178 181 184 187 190 193 196 199 202 205 208 211 214 217 220 223 226 229 232 235 238 241 244 247 250 253 256 259 262 265 268 271 274 277 280 283 286 289 292 295 298 301 304 307 310 313 316 319 322 325 328 331 334 337 340 343 346 349 352 355 358 361 364 367 370 373 376 379 382 385 388 391 394 397 399 402 405 408 411 414 417 420 423 426 429 432 435 438 441 444 447 450 453 456 459 462 465 468 471 474 477 480 483 486 489 492 495 498 501 504 507 510 513 516 519 522 525 528 531 534 537 540 543 546 549 552 555 558 561 564 567 570 573 576 579 582 585 588 591 594 597 599 602 605 608 611 614 617 620 623 626 629 632 635 638 641 644 647 650 653 656 659 662 665 668 671 674 677 680 683 686 689 692 695 698 701 704 707 710 713 716 719 722 725 728 731 734 737 740 743 746 749 752 755 758 761 764 767 770 773 776 779 782 785 788 791 794 797 799 802 805 808 811 814 817 820 823 826 829 832 835 838 841 844 847 850 853 856 859 862 865 868 871 874 877 880 883 886 889 892 895 898 901 904 907 910 913 916 919 922 925 928 931 934 937 940 943 946 949 952 955 958 961 964 967 970 973 976 979 982 985 988 991 994 997 999 1000

tate of para-methoxyphenylguanylurea penicillin forms which is collected and dried. The material has an aqueous solubility of about 0.2% and with an actual analysis of 1050 units per milligram as compared with a theoretical analysis of 1090 units per milligram.

EXAMPLE 12

*Beta-phenylisopropylguanylurea penicillin*4.0 grams of beta-phenylisopropylguanylurea nitrate dissolved in 150 milliliters of 50% ethanol are added slowly to a solution of 7 grams of potassium penicillin G dissolved in 150 milliliters 50% ethanol. On chilling to 4° C. for one hour the desired beta-phenylisopropylguanylurea salt of penicillin is obtained in crystalline form. The material is collected, washed with water and dried in vacuo. The material has a theoretical potency of 1065 units per milligram and on analysis is found to contain 1020 units per milligram. The material is soluble in water to the extent of 0.122%.

EXAMPLE 13

*Para-tolylguanylurea penicillin*6.0 grams of para-tolylguanylurea hydrochloride are dissolved in 60 milliliters of 50% ethyl alcohol and added slowly to a solution of 10.8 grams of potassium penicillin G in 60 milliliters of 50% ethyl alcohol at 50° C. Crystallization of the desired para-tolylguanylurea salt of penicillin begins almost immediately. After one hour at 4° C. the compound is collected, washed with water and dried. The material has a theoretical content of 1130 units per milligram and on analysis is found to contain 1070 units per milligram. The material has an aqueous solubility of approximately 0.2%.

EXAMPLE 14

*Phenylguanylurea penicillin*5.0 grams of phenylguanylurea hydrochloride are dissolved in 50 milliliters of 40% ethanol and added slowly to a solution of 9 grams of sodium penicillin G dissolved in 40% ethanol; a heavy crystalline precipitate of phenylguanylurea penicillin being formed. This material is collected in a sintered glass funnel, washed with water and dried in vacuo. The product is soluble to the extent of approximately 0.2% in water with an actual analysis of 1049 units per milligram as compared to a theoretical analysis of 1159 units per milligram.

EXAMPLE 15

Dibutylguanylurea penicillin

0.01 mole of dibutylguanylurea nitrate in 100 milliliters of ethyl alcohol is mixed with 0.01 mole of sodium penicillin dissolved in 100 milliliters of ethyl alcohol. Sodium nitrate which

forms is separated by filtration. The dibutylguanylurea penicillin is precipitated from the solution by the addition of 600 milliliters of ethyl ether. A white, amorphous, therapeutically active powder is obtained which may be separated by filtration.

EXAMPLE 16

Thiazolylguanylurea penicillin

10 0.02 mole of thiazolylguanylurea nitrate in 200 milliliters of propanol is reacted with 0.02 mole of potassium penicillin dissolved in 200 milliliters of butanol. The potassium nitrate formed is separated and the thiazolylguanylurea penicillin salt formed in the reaction is precipitated by the addition of 1500 milliliters of ethyl ether. The precipitate is filtered off, washed with ethyl ether, and thereby is obtained a white, amorphous, therapeutically active powder.

EXAMPLE 17

N-phenyl-N-methylguanylurea penicillin

25 0.01 mole of N-phenyl-N-methylguanylurea nitrate dissolved in 100 milliliters of 2-ethoxyethanol is reacted with 0.01 mole of ammonium penicillin dissolved in 100 milliliters of 2-ethoxyethanol. The thus formed N-phenyl-N-methylguanylurea penicillin salt is precipitated by the addition of 800 milliliters of ether and is separated from the solvents by filtration. The salt is washed, first with ether, then with water, and thereby is obtained a white, amorphous, therapeutically active powder.

30 35 Having thus set forth by description and example certain aspects thereof, as our invention we claim:

1. The salt of penicillin and a compound selected from the group consisting of guanylurea, N-alkylguanylurea, N,N - dialkylguanylurea, N-cycloalkylguanylurea, N-monocyclic arylguanylurea, N-monocyclic haloaryl guanylurea, N-arylguanylurea, N-monocyclic lower alkoxyarylguanylurea, N-monocyclic lower alkaryl guanylurea, N-alkyl-N-aryl-guanylurea, N-guanylurea, N-carbamyl guanylurea and N-monocyclic arylguanylurea.
2. The salt of penicillin and N-cyclohexylguanylurea.
3. The salt of penicillin and N-octylguanylurea.
4. The salt of penicillin and N-beta-phenylethylguanylurea.
5. The salt of penicillin and N-phenylguanylurea.
6. The salt of penicillin and N-parachlorophenylguanylurea.
7. The salt of penicillin and N-alkylguanylurea.
8. The salt of penicillin and N-monocyclic arylguanylurea.

60 65 LAWRENCE RITTER.
JOSEPH F. WEIDENHEIMER.
